UNITED STATES PATENT OFFICE.

WILLIAM R. HAMILTON, OF DEWEY, OKLAHOMA.

TURBINE-GOVERNING MECHANISM.

1,295,027.

Specification of Letters Patent. Patented Feb. 18, 1919.

Application filed May 10, 1915. Serial No. 27,211.

To all whom it may concern:

Be it known that I, WILLIAM R. HAMILTON, a citizen of the United States, residing at Dewey, in the county of Washington and 5 State of Oklahoma, have invented certain new and useful Improvements in Turbine-Governing Mechanism, of which the following is a specification.

This invention relates to an improvement 10 in an apparatus for generating electricity, to be used for lighting purposes and the like, and the object is to provide means for rotating the generator for generating electricity.

15 A further object is in the provision of means for controlling the speed of rotation of the driving member.

The invention consists of certain novel 20 features of construction and combinations of parts which will be hereinafter described and pointed out in the claims.

In the accompanying drawings:

Figure 1 is a view in top plan of the invention;

25 Fig. 2 is a view in side elevation;

Fig. 3 is a view in elevation of the driving member, showing the front plate removed;

30 Fig. 4 is an enlarged detail sectional view showing the valve and its operating mechanism; and

Fig. 5 is a perspective view showing the lever and its connections disassembled.

A, represents a shaft upon which is 35 mounted the generator B and the motor C.

A rotor 1 mounted on the shaft A, is provided with blades 2 on the periphery thereof, and rotates within the casing 3. An inlet opening 4 is formed in the casing for the introduction of steam from any suitable source 40 of supply, and leading from the opening are channels or passages 5. Leading from the channels or passages 5 are ports or ducts 6 and 7, for conducting the steam to the blades 45 of the rotor. The port 6 extends downwardly, and the port 7 extends upwardly, so that the rotor will receive two impulses to each revolution, or in other words there is a constant pressure being exerted against the 50 rotor at two opposite points for causing the rotor to be rotated.

Needle valves 8 are slidably mounted in the casing 3, and extend through the ports 6 and 7 for controlling the admission of steam 55 to the rotor. Brackets 9 are connected to the casing 3 and the other terminals of the

valves 8 project through the brackets. Springs 10 surround the valves, one terminal of the springs bearing on the brackets, and the other terminal is engaged by a nut 11 screwed upon each of the valves for normally forcing the valves outward to afford an unobstructed passage for the steam through the ports 6 and 7. An adjustable collar 12 is mounted on the needle valves 8 60 which is adapted to engage the brackets 9 for limiting the outward movement of the valves.

Crutch bolts 13 are adjustably connected to the casing 3 by means of nuts 14, and 65 mounted upon the ends of the bolts are heads 15. These heads are provided with a bifurcation 16 in which levers 17 are pivotally mounted. The crutch bolts are preferably made square at their free end, and the heads 70 15 have the bores thereof made square to fit over the squared ends of the bolts. Set screws 18 carried by the heads 15 are adapted to be screwed into engagement with the bolts for holding the heads at the proper 75 elevation.

A governor consisting of a stationary block 19 is fastened to the shaft A, and a movable block 20 which is also mounted on the shaft. The two blocks are connected together by means of toggles 21. A spring 22 mounted on the shaft A has one end thereof in engagement with an adjustable collar 23 on the shaft A, and the other terminal in engagement with the movable block 20, for exerting a pressure against the movable block 20 to cause the toggle links to remain practically parallel with the shaft A. 85 90

An end of each lever 17 is connected to the movable block 20 of the governor, and 95 the other terminal of each lever engages a valve 8.

When the shaft A begins to revolve at a speed which is too high for the purposes required the levers will be actuated by the movement of the block 20 moving toward the stationary block 19, causing the valves to be moved inward for closing the steam ports and thereby cutting off the steam to the rotor. This movement will generally be 100 gradual, but the timing of the action of the levers on the valves is regulated by the adjustment of the crutch heads 15 on the bolts 13. 105

I claim:

110 1. The combination of a fluid pressure motor, a governor mounted on the shaft

thereof, a plurality of spring actuated needle-valves in the sides of the motor, crutch bolts connected to the motor, adjustable heads connected to the bolts, levers pivotally connected to the heads, a terminal of each lever connected to the governor, and the other terminal of each lever adapted to actuate a needle-valve upon the movement of the governor, and means for adjusting the crutch heads upon the crutch bolts.

2. The combination of a fluid pressure motor, a governor on the shaft thereof, a plurality of spring actuated needle-valves in the sides of the motor, levers connected to the governor extending in the path of the valves, operated and controlled by the movement of the governor for actuating the needle-valves, adjustable crutch bolts to which the levers are fulcrumed, brackets connected to the motor for guiding the valves, and adjustable collars connected to

the valves adapted to engage the brackets for limiting the outward movement of the valves with relation to the adjustable fulcrumed levers.

25

3. The combination of a fluid pressure motor, a governor on the shaft thereof, a plurality of spring actuated needle-valves in the sides of motor, levers connected to the governor extending in the path of the valves, operated and controlled by the governor for actuating the needle-valves, crutch bolts on the motor to which the levers are fulcrumed, and means for adjusting the position of the crutch bolts for timing the actuation of the valves by the levers.

30

In testimony whereof I affix my signature in the presence of two witnesses.

WILLIAM R. HAMILTON.
